UNITED STATES PATENT OFFICE.

ALFRED W. BRUCE, OF NEW YORK, N. Y.

LOCOMOTIVE BOILER.

Continuation of application Serial No. 64,347, filed October 23, 1925, and in Canada October 18, 1926.
This application filed January 27, 1927. Serial No. 164,031.

This application is a continuation of my application for Letters Patent Ser. No. 64,347 filed Oct. 23, 1925.

My invention relates to locomotive boilers of the general class or type in which the side walls of the fire box are formed of water tubes, and comprises a construction in which all staybolts may be omitted in the most highly heated parts of the fire box, and provides for increased heating surfaces and more rapid circulation, with the result that greater efficiencies per pound of coal are more readily obtained. To this end, in my improved construction I employ a hollow mud ring on the sides and ends of the fire box base, into which are connected rows of vertical water tubes, which form the side walls of the fire box. The water tubes are of the same size and shape and may be interchanged and removed without disturbing other members of the fire box leading into a steam drum, which extends into the barrel of the boiler and affords proper circulation between the boiler barrel and fire box heating spaces. I also provide proper control of the flow of steam between the water level of the boiler and the steam dome, and thus prevent the carrying over of water into the dry pipe. These and various other objects are effected in my improved construction without altering the size and shape of the boiler, which, in general contour and exterior arrangement, is similar to the boilers now in use. My invention also comprises the various features which I shall hereinafter describe and claim.

The improvement claimed is hereinafter fully set forth.

In the accompanying drawings: Figure 1 is a vertical longitudinal central section through a locomotive boiler embodying my invention; Fig. 2, a one-half horizontal longitudinal section through the middle plane of the boiler; Fig. 3, a view, in elevation, of the back head of the boiler; Figs. 4 and 5, vertical sections, on the lines IV—IV and V—V, respectively, of Fig. 1; Fig. 6, a plan of the hollow mud ring; Fig. 7, a front view, partly in section, of the mud ring; Fig. 8, a similar section through the mud ring, on the line VII—VIII of Fig. 6; Fig. 9, a similar section, showing an alternative construction for the attachment of the mud ring to the boiler barrel; Fig. 10, a ver-

tical longitudinal central section, showing the application of my invention in a locomotive boiler having a combustion chamber; Fig. 11, a one-half horizontal longitudinal middle section of the structural modification shown in Fig. 10; Figs. 12, 13 and 14, vertical transverse sections on the lines XII—XII, XIII—XIII, and XIV—XIV, respectively, of Fig. 10; Fig. 15, a section, on the line XV—XV of Fig. 13; and, Fig. 16, a vertical transverse section through the firebox of a modified form of my invention, in which two water and steam drums instead of one are employed.

In the practice of my invention, referring descriptively to the specific embodiment thereof which is herein exemplified, and first to Figs. 1 to 9, inclusive, the locomotive boiler comprises three main sections, the firebox, A, the boiler barrel, B, through which extends a plurality of fire tubes, 1, in the ordinary manner, and the smoke box, C. The forward end of the fire box, A, is connected by a throat sheet, 2, to the boiler barrel, B, and the mud ring, 3, in the usual manner, and a back head, of the usual form, made up of two spaced apart sheets or plates, 5 and 6, with outwardly extending flanges and suitable cover plates, the two sheets being stayed together by staybolts, 7, thus providing a water space between the plates, 5 and 6. The back head is provided with a suitable fire door opening, 8, and an opening, 9, for the water drum manhole cover, 9a. The mud ring, 3, is hollow and preferably integral. It communicates with, and forms the bottom support of, a plurality of water tubes, 10, which are set closely together, forming the side walls of the fire box, and are connected, at their upper ends, with a steam drum, 11, which extends horizontally and forwardly into the barrel, B, of the boiler.

Connected to the front end of the mud ring, 3, and extending upwardly and rearwardly to the back head, 4, are arch tubes, 12, which support the fire brick arch, 13, in a manner similar to the usual construction. The upper surface of the grate, 14, lies approximately in the plane of the top surface of the mud ring, 3.

The fire box, A, is connected to the boiler barrel, B, back flue sheet, 22, and throat sheet, 2, by a roof or wrapper sheet, 15,

which is wholly independent of the fire box proper, is preferably, as shown, curved concentrically with the boiler barrel, and performs primarily the function of a rigid connecting member for the fire box and boiler barrel, and secondarily, that of a closure or housing for the top of the fire box, to prevent the escape of gases of combustion therefrom, without being, or being required to be, a member performing the function of the ordinary wrapper sheet known in practice, i. e., that of forming the wall of a steam space in a boiler, where it is, in the operation thereof, continuously subject to internal pressure. Suitable lagging or insulating material, 16, is provided between the outside of the water tubes, 10, and the inside of the wrapper sheet, 15.

The mud ring, 3, has an apertured forward face, 3^a, for a suitable elbow connection, 17, which connects the bottom of the barrel, B, with the forward side of the mud ring, and supplies the mud ring with feed water for the side wall tubes, 10, the arch tubes, 12, and the back head, 4. The mud ring has, in its upper surface, spaced apart apertures, 18 and 18^b, for the reduced lower ends of the side tubes, 10, and for the arch tubes, 12, respectively, which may be secured to the mud ring by upsetting of their ends on the inner surface of the top plate of the mud ring. Communication with the back head, 4, is provided through the apertures, 18^b. The mud ring is provided with detachable bottom cover plates, 19, which permit access to the lower ends of the side wall tubes, 10, for setting, cleaning, etc. The top of the mud ring has vertical flanges, 20, for connection with the throat, roof and side sheets, and also horizontal flanges, 21, for connection of the back head, 4. The bottom of the ring at front and back, is provided with the usual flanges and connections for the fire box supports.

The steam dome, 23, is connected, in the usual manner, to the top of the cylindrical barrel, B, at a point between the back tube sheet, 22, and the front end of the horizontal steam drum, 11. From the steam dome, a dry pipe, 24, extends forwardly through the front tube sheet, 25, to a throttle valve (not shown) in the smoke box, C, in the usual manner. Between the top of the steam drum and the top of the cylindrical barrel, B, are interposed circulating plates, 26, which form a channel through which steam delivered from the forward end of the steam drum, 11, passes upwardly and back to the dome, 23, and then forwardly through the dry pipe, 24. Steam which is formed within the cylindrical shell of the boiler barrel, B, and below the steam circulating plates, 26, is also compelled to pass forward of the forward end of the circulating plates and then upward and back to the dome, 23,

through this same channel. This construction insures the obtaining of dry steam for admission to the dry pipe, 24, as the lifting of water from the water level in the boiler shell and steam drum to the top of the dry pipe is thus avoided.

In Fig. 9 I have shown a modified construction of connection between the mud ring, 3, and the barrel, B, of the boiler. The throat sheet, 2, and back tube boiler sheet, 22, are flanged externally for connection to the top of the mud ring, and the top of the forward transverse member of the mud ring is provided with an aperture, 3^b, to permit the water from the barrel, B, to feed directly into such forward portion of the mud ring.

In Figs. 10 to 15, inclusive, I have shown a further structural modification of my invention, in which the fire box, A, has been increased in length so as to include a combustion chamber, D. The side walls and part of the top of the combustion chamber are formed of water tubes, 10^a, which conform in shape, above the centre of the boiler, to the side tubes, 10, and, below the centre of the boiler, are substantially semi-circular in shape. The tubes, 10^a, are connected, at their tops, to the steam drum, 11, and, at their bottoms, to a header, 31, which, at its front end, extends through the throat sheet, 2, and communicates with the boiler barrel, B, and, at its back end, terminates against the front face of the mud ring, 3, and the lower forward face of the fire box arch, 13.

The header, 31, provides a water passage from the boiler barrel, B, to the bottom ends of the water tubes, 10^a, of the combustion chamber. This water passage through the header, 31, is separate from, and has no connection with, the water feed to the mud ring, 3, through the water-supply member, 17. The header, 31, is provided with removable bottom plates, 32, which are rendered accessible by taking down the water supply member, 17. The water tubes, 10^a, are covered by suitable lagging, 16, on their outer faces, which lagging is held in place by a light metal jacket, 33, the upper end of which is fastened to the wrapper sheet, 15, and the lower end to the header, 31. The space between the rear end of the jacket, 33, and the top of the mud ring, is filled with a fire brick wall, 34, which is supported on top of the mud ring, 3, and is held in position by the removable gusset plates, 35, which form a backing for the brick wall, 34. The gusset plates are held in position by the tie plates, 36.

The lagging between the wrapper sheet, 15, and the tubes, 10 and 10^a, may be applied in plastic form, or in the shape of preformed blocks.

My improved construction attains the following advantageous results, to wit: the elimination of staybolts in the fire box zones

which are subjected to intense heat, with a consequent great saving in maintenance; a substantial increase in heating surface, with consequent improved water circulation; the disposal of the water tube side members in single rows, of the same size and shape, which are interchangeable and removable, and give a simplicity in construction over other types; the stiffening action of the wrapper sheet on the entire boiler structure, which sheet also permits attachment of the fittings for the cab and auxiliary appliances; the use of a hollow mud ring to supply feed water to the tubes and back head and detachable bottom plates therefor, providing access to the bottoms of the side tubes; by making the ring integral, a stiffening of the whole fire box structure is effected, and trouble with water tight joints and connections is eliminated; the forward extension of the steam drum to the forward portion of the boiler barrel, which compels proper circulation between the barrel and the fire box heating spaces, and eliminates the carrying over of water into the dry pipe; and the retention of the usual shape of the fire box, which permits the use of the ordinary cab and other attachments.

Fig. 16 shows a further structural modification of my invention in which a pair of drums, 11, 11, instead of a single drum, is applied. Each set of side tubes, 10, leads into one of the drums, 11, and the drums are preferably not connected, so that the steam from each flows forwardly into the barrel, as in the other forms of my invention. The space between the drums is closed by a fire-resisting wall, 37, thus completing the enclosure of the fire box.

I claim as my invention and desire to secure by Letters Patent:

1. In a locomotive boiler, the combination of a barrel and a fire box; the fire box having a steam drum at the top thereof, side wall water tubes leading into said drum, a hollow mud ring connected to the bottom of the tubes to supply feed water therefor; and a wrapper sheet rigidly secured to the barrel and the fire box, forming a stiffening means for the parts of the fire box, and a housing for the sides and top of the fire box.

2. In a locomotive boiler, the combination of a fire box comprising a hollow mud ring, a back head having water communication with the mud ring, side water tubes connected at their lower ends to the mud ring, a water drum into which the side tubes lead; a barrel; a wrapper sheet securing the back head, barrel, and fire box rigidly together and forming a stiffening means and a housing therefor; and a feed connection between the forward side of the mud ring and the barrel, whereby water received from the barrel is fed to said tubes, back head and drum.

3. In a locomotive boiler, the combination

of a barrel; a steam dome and a dry pipe therefor; a fire box; a hollow mud ring forming part of said fire box and disposed so as to receive feed water from the barrel; a drum; water tubes in the fire box connecting the mud ring and the drum, the drum extending from the rear end of the fire box to a point forward of the dome; and means for preventing the steam from the drum or barrel from carrying water over into the dry pipe.

4. In a locomotive boiler, the combination of a barrel; a steam dome and a dry pipe therefor; a fire box; a hollow mud ring forming part of said fire box disposed so as to receive feed water from the barrel; a drum; water tubes in the fire box, connecting the mud ring and the drum, the drum extending from the rear end of the fire box to a point forward of the dome; and plates associated with the drum for preventing the steam from the barrel from carrying water over into the dry pipe.

5. In a locomotive boiler, the combination of a barrel and a fire box; the fire box having a steam drum at the top thereof; side walls formed of water tubes leading into said drum; a hollow mud ring connected to the bottom of the tubes and supplying feed water therefor; a combustion chamber forming the forward part of the fire box; and a wrapper sheet securing the barrel and fire box rigidly together, and forming a stiffening means and a housing for the sides and top of the fire box and combustion chamber.

6. In a locomotive boiler, the combination of a barrel; a fire box, comprising a combustion chamber and a fire chamber, the combustion chamber terminating in rear of the barrel; a back head, closing the rear of the fire chamber; a drum, extending forwardly from the backhead, through the fire and combustion chambers; side water tubes, connected to said drum, and forming therewith the sides and roof of the fire and combustion chambers; means for feeding water from the barrel to the side water tubes; and a wrapper sheet, secured to the barrel and to the fire box, and performing the functions of rigidly connecting said members together, and forming a housing, covering the roof of the fire box.

7. In a locomotive boiler, the combination of a barrel; a fire box, comprising a combustion chamber and a fire chamber, the combustion chamber terminating in rear of the barrel; a back head, closing the rear of the fire chamber; a drum, extending forwardly from the back head, through the fire and combustion chambers; side water tubes, connected to said drum, and forming therewith the sides and roof of the fire and combustion chambers; means for feeding water from the barrel to the water tubes, comprising a header with which the tubes in the

combustion chamber are connected and a mud ring with which the tubes in the fire chamber are connected; and a wrapper sheet, secured to the barrel and to the fire box, and performing the function of rigidly connecting said members together, and forming a housing covering the roof of the fire box.

8. In a locomotive boiler, the combination of a barrel; a fire box, comprising a combustion chamber and a fire chamber, the combustion chamber terminating in rear of the barrel; a back head, closing the rear of the fire chamber; a drum, extending forwardly from the back head, through the fire and combustion chambers; side water tubes, connected to said drum, and forming therewith the sides and roof of the fire and combustion chambers; a throat sheet filling in the triangular side spaces at the front of the combustion chamber; and a wrapper sheet, secured to the barrel, the throat sheet, and the fire box, and performing the function of rigidly connecting said members together, and forming a housing covering the roof of the fire box.

9. In a locomotive boiler, the combination of a barrel and a fire box, the fire box comprising a drum, a hollow mud ring, side tubes connecting the mud ring and drum; a back head, connected to the mud ring; and a wrapper sheet rigidly securing the mud ring, back head, and barrel together, and forming a stiffening means therefor.

10. In a locomotive boiler, the combination of a barrel and a fire box; the fire box comprising a drum; a hollow mud ring; side tubes connecting the mud ring and drum; a back head, connected to the mud ring; a wrapper sheet rigidly securing the mud ring, back head and barrel together, and forming a stiffening means therefor; and insulating material between the tubes and wrapper sheet.

11. In a locomotive boiler, the combination of a barrel; a steam dome at the top of the barrel; a fire box; water tubes at the sides of the fire box; circulating connections between the tops and bottoms of the tubes and the barrel, the top connection in the barrel extending forwardly of the steam dome and disposed so as to deliver the circulating water and steam generated in the fire box into the barrel at a point in advance of the steam dome.

12. In a locomotive boiler, the combination of a barrel; a steam dome at the top of the barrel; a fire box; water tubes at the sides of the fire box; circulating connections between the tops and bottoms of said tubes and the barrel, the top connection in the barrel extending forwardly of the steam dome; and circulating plates between the top connection and the barrel extending from the rear end of the barrel to a point forward of the steam dome, whereby steam from the upper portion of the barrel is

caused to pass forwardly of said plates to reach the steam dome.

13. In a locomotive boiler, the combination of a barrel; a steam dome at the top of the boiler barrel; a fire box comprising a fire chamber and a combustion chamber; water tubes at the sides of the fire chamber and combustion chamber; circulating connections between the tops and bottoms of said tubes and the barrel; the top connection in the barrel extending forwardly of the steam dome and disposed so as to deliver the circulating water and steam generated in the fire box into the barrel at a point in advance of the steam dome.

14. In a locomotive boiler, the combination of a barrel, a fire chamber and a combustion chamber disposed end to end, the fire chamber being of greater cross section than the combustion chamber; and having a hollow mud ring through which feed water is supplied to water heating spaces about the fire box; a brick wall supported by the mud ring and filling the space in the end of the fire chamber which extends beyond the combustion chamber; and a wrapper sheet, secured to the barrel and to the fire box, and performing the function of rigidly connecting said members and forming a housing covering the roof of the fire box and combustion chamber.

15. In a locomotive boiler, the combination of a barrel and a fire box having a fire chamber; a throat sheet securing the barrel and fire box together; a mud ring; insulating material, supported by the mud ring, exposed to the interior of the fire chamber and filling the triangular spaces between such chamber and the boiler shell; and removable means for holding the insulating material in position.

16. In a locomotive boiler, the combination of a barrel and a fire box; water spaces about the fire box; a drum, into which the water spaces lead, extending forwardly into the forward part of the barrel; and a dry pipe housed in the drum and extending forwardly in the barrel.

17. In a locomotive boiler, the combination of a waist or barrel, having a plurality of fire tubes; and a fire box, the forward end of the fire box being disposed to the rear of, and connected to the rear of, the barrel, the portion thereof forward of its grate containing a combustion chamber, said fire box comprising a water space back head communicating with the barrel, a hollow mud ring, an upper steam delivery drum, and water tube side walls connecting the drum and mud ring; and a wrapper sheet, secured to the barrel and to the firebox, and performing the function of rigidly securing said members together, and forming a housing covering the roof of the fire box.

ALFRED W. BRUCE.
